UNITED STATES PATENT OFFICE.

PATRICK F. FOLEY, OF BROOKLYN, NEW YORK.

DOOR-LOCKING DEVICE.

1,217,586.

Specification of Letters Patent. Patented Feb. 27, 1917.

Application filed December 11, 1916. Serial No. 136,140.

To all whom it may concern:

Be it known that I, PATRICK F. FOLEY, a citizen of the United States, and resident of the borough of Brooklyn, county of Kings, city and State of New York, have made a certain new and useful Invention Relating to Door-Locking Devices, of which the following is a specification, taken in connection with the accompanying drawing, which forms part of the same.

This invention relates especially to door locking devices which may be used with good results in connection with elevator door locking and controlling apparatus, such as is covered by my Patent 1,181,217 of May 2, 1916. The locking device may comprise an angular slotted door catch adapted to coöperate with a locking roll or member mounted, for instance, on the jamb of the door, so that when the door is closed the locking member enters the slotted catch and forces this member and a connected locking bolt transversely through the distance controlled by the closing movement of the door. A detent coöperates with the locking bolt so as to hold it in any such locked position so that the door is prevented from opening even though it has not completely closed, and this is of course a decided advantage, especially in the case of elevator doors. A cushioning device is preferably associated with the locking bolt so as to cushion the closing action of the door and correspondingly minimize jar and noise.

In the accompanying drawing showing in a somewhat diagrammatic way illustrative embodiments of this invention

Figure 1 is a vertical section through an elevator door locking device.

Fig. 2 is a transverse section thereof taken substantially along the line 2-2 of Fig. 1.

Fig. 3 is a sectional elevation of a modification adapted for use on ordinary swinging doors; and

Fig. 4 is a side sectional view thereof.

The elevator door locking device may coöperate, for instance, with an elevator shaft door of any desired type, such as the horizontal sliding door 55, mounted on hangers engaging the track 99 of any suitable construction so as to slide back and forth thereon. The coöperating door locking devices which may with advantage be mounted on the upper end of the door and the co-

operating door casing 98 as shown in greater detail in Fig. 1 may comprise an angularly arranged door catch of any desired description coöperating with a suitable locking member which preferably is spring pressed or otherwise normally held in position to receive the catch as the door closes, a cushioning device being, if desired, associated with the locking member so as to cushion the closing action of the door and minimize jar and noise, while at the same time the door is locked against withdrawal as soon as the angular catch and locking member engage.

The catch 62 may as indicated in Fig. 1 be provided with an angularly arranged slot 56 and may be mounted either on the door or casing, although as shown it is bolted or otherwise secured adjacent the upper end of the door 55. The coöperating locking member may be in the form of a locking roll 57 mounted on the locking slide or bolt 66 mounted in suitable guides, such as 73, in a lock casing 28, which may be bolted or otherwise secured to the elevator shaft adjacent the door opening. This locking bolt may be provided with a suitable cushioning device as by forming a cushioning plunger 69 on the end of the stem 68 of the bolt and providing a coöperating cushioning cylinder 71 in which this plunger fits with sufficient tightness and which may be filled with any suitable cushioning fluid 72, such as oil, glycerin or air in some cases. One or more restricted throttling passages, such as 70, may be formed in this plunger to allow the passage of the cushioning fluid therethrough and give the desired cushioning action, the size or number of these passages being of course selected or controlled for this purpose. It is in some cases desirable to provide a quick return valve of any suitable description in this plunger or in connection therewith, such as the valve 102, normally held by its coöperating spring 103 over the enlarged return passage 101 in the plunger, but adapted to open and allow the freer passage of the cushioning fluid as the locking bolt moves upward. It is desirable to have this locking bolt returned by any suitable means, such as the return spring 67, to its upper receiving position where it is adapted to enter the end of the slot in the door catch and a suitable alining device, such as the alining bolt and lock nut 104 may be used.

to adjust this normal receiving position of the locking bolt after the parts have been assembled.

- Any suitable detent device may be used 5 in connection with the locking bolt to hold it in locking position after it has been moved downward more or less by engagement with the catch, and if desired a toothed detent 75 may be mounted in any desired way adjacent 10 the bolt so as to coöperate with the series of ratchet teeth 74 on the bolt. This detent may be mounted on the detent bar 76 carried in suitable sliding bearings or yokes 78 mounted in the lock casing and preferably 15 formed with means to prevent its undesirable rotation which may be conveniently effected by forming one end of the detent bar 100 of square or polygonal cross-section. The detent spring 79 may normally 20 force the detent into holding engagement with the ratchet on the locking bolt as by engaging a washer 80 coöperating with a collar 81 secured to the detent bar.

In this way when the shaft door is closed 25 the slotted door catch engages the locking roll during the last few inches of the door's travel and forces the roll and connected locking bolt downward, the ratchet teeth slipping past the detent, but preventing any 30 backward movement so that the door catch is locked against retraction as soon as any substantial engagement with the locking member takes place. At the same time the closing movement of the door is retarded or 35 cushioned as soon as the catch and locking member engage, by the cushioning plunger and cylinder described and also by the return spring 67 which resists this movement, so that under normal conditions the closing 40 impact of the door is considerably reduced and the door is effectively held in closed or substantially closed position because the locking bolt holds just as effectively whether the roll has entirely or partly reached the 45 end of the slot 56. The locking device may be released in any suitable way, either automatically or manually, as for example, a manual releasing lever such as 53 may be mounted on the shaft door so as to swing 50 about the pivot 52 when operated by the handle 51. The upper slotted end of this lever may engage a suitable pin 61 on the releasing bolt 54 which may as indicated be mounted in the guides or brackets 60 secured 55 to the door in such position as to be substantially in line with the extension 59 of the detent bar which may project through a suitable slot in the locking bolt and extend outside the lock casing. In this way the releasing 60 lever may force back the releasing extension of the detent so as to release the locking bolt and allow its return under the action of the return spring and the opening door, the releasing lever being so arranged 65 that by pulling it in the direction of the

arrow in Fig. 2 the locking bolt is released and the door simultaneously opened by the same movement. If desired, also, the lock may be released from outside the shaft door by providing a suitable release key, such as 63, revolubly mounted on the bracket 64 and having its end projecting through a suitable slot 65 in the door so as to be engaged by a key or opening device and rotate the releasing arm 58 sufficiently to force back the 70 detent extension 59 and release the detent from the bolt in the same manner, thus providing an emergency release of the parts which is desirable for some purposes.

It is sometimes desirable to provide an automatic releasing arrangement on the elevator car so that when the car is in proper co-operation with the door opening the locking device may be automatically released and in some cases it is also of advantage to arrange a suitable controller in connection with the operating device of the car as described in said patent. For this purpose the locking device may be provided with a suitable releasing member or contact arm coöperating 80 with a cam or releasing device carried by the elevator car which may, if desired, be actuated when the car is stopped at one of the door openings so as to release the lock under these conditions. An illustrative arrangement of this character is shown in Figs. 1 and 2 as comprising the releasing contact arm 83 mounted on the detent bar and having a suitable cam portion coöperating with the angular or cam face on the 90 collar 81 so that when this releasing arm is swung inward against its spring 97 as by contact between the cam 24 and the roll 27 on this contact arm the cam action forces the detent bar backward so that the ratchet 95 and detent are disengaged and the roll locking device is released.

It is also desirable to have a suitable control switch or device arranged in connection with the door locking device so that when the door is closed the elevator may be operated and not otherwise, and if desired, controlling devices such as described in said patent may be used for this purpose, including the wires 45 connected to the cams or 100 contact members 24, 25 so that when the car is opposite a door opening the controller circuit through these wires may be normally closed by a suitable lock or door switch, such as 90, shown in Fig. 1. This door 105 switch or contact lever 90 may be pivoted about the point 91 and may have a suitable insulated contact 92 adjustably or otherwise mounted in the switch member in such position as to be engaged by the projection or 110 operating lug 93 on the lateral extension 94 of the locking bolt so that when the locking bolt is depressed at the time the door is locked this switch moves in the direction of the arrows so as to separate the switch con- 115

acts 89 and break the controller circuit at this point. For this arrangement the controller circuit may comprise the wires 45 connected to the releasing contact cam 24 of conducting metal which is preferably insulated from its cam bracket 34. When in engagement with the releasing contact arm 83 this contact then supplies electricity therethrough to the flexible connection 87 shown in Fig. 2 to the contact piece 88. The contact lever 90 of the door switch which may be spring-actuated as indicated to normally hold the contacts 89 closed is connected by the flexible electric braid or connector 86 to the release contact arm 84 provided with a similar roll 26 which under these conditions is in electric contact with the corresponding contact cam 25 of similar construction.

A generally similar cushioned bolt locking device is shown in Figs. 3 and 4 as adapted for use in locking an ordinary swinging or other door 98 on which, if desired, the lock casing 28 may be mounted as by the screws 144. This lock casing may be provided with guides to accommodate the locking bolt 66 so that it can have vertical movement together with its projecting locking member 139 which may project through a suitable slot 147 and carry the friction roll or bushing 141 held in place as by the washer 57 and screw 140. This locking roll may cooperate with a suitably slotted door catch on the door jamb, the plate 137 secured to the door jamb as by the screws 138 being, if desired, formed with the inclined slot 56 with which this roll co-operates. The locking bolt and roll are normally held in raised position as by the return spring 67 forcing them upward into engagement with a suitable alining device or screw 152 which determines the upper position of this bolt and roll so that in closing the door the roll enters the slotted catch on the jamb. The further closing movement of the door forces the locking bolt downward against the action of its return spring 67 and this downward movement is preferably further cushioned by a liquid or other cushioning device which may comprise the locking bar 106 on the bolt carrying the cushioning plunger 108, 109 in the cylinder 107 containing any suitable liquid 114, such as oil, glycerin, etc. The closing movement of this plunger forces liquid through the restricted throttling passage 113 which is shown as somewhat exaggerated in size for the sake of clearness and the regulating screw 112 may be adjusted so as to still further close this passage to the extent desired and insure the corresponding degree of cushioning action found most desirable with the particular door and conditions of use. A return valve, such as 111, may be used to promote the quick return of the locking bolt and connected parts so that when the bolt and connected plunger are raised the

liquid quickly passes into the upper end 115 of the return passage 110 and up past this return valve 111.

A series of notches may be formed on the locking bolt so as to be engaged in any position by the notched detent 75 which is slidably mounted in the guideway 124 in the casing and is secured to the detent bar 118 having its end 117 engaged by a detent spring 134 which may encircle the reduced extension 116 of this detent bar. This detent thus engages and holds the locking bolt in its lowered locking position when the door is entirely or nearly closed and this detent may of course be released in any suitable way in connection with a door knob or other device. An illustrative arrangement of this character is indicated as comprising the rack teeth 119 on the detent bar with which co-operates the toothed sector 120 secured on the square shank or bar 121 on which the door knobs 122 may be secured in the usual way. Thus rotation of a door knob manually withdraws this detent and allows the locking bolt to rise and the door to open. The detent may, however, be positively held or locked in this holding position indicated in Fig. 3 by suitable devices such as the locking lug 125 on the detent bar co-operating, if desired, with the pivoted locking lever 129 normally forced as by the spring 133 down against the stop 128. One or more tumblers or releasing devices 131 may co-operate with this locking lever to hold it in its raised locking position shown in Fig. 3 and these releasing devices may be pressed into this position as by the spring 132 forcing their projecting portions 127 into contact with the casing. When, however, a key, such as 145 shown in dotted lines is inserted into the key-hole 130 and turned around into contact with these releasing devices they are forced laterally toward the stop 126 so that they are moved out of contact with the locking lever 129 which thereupon falls into dotted position away from the locking lug so that the detent bar and detent can be once more released to allow the door to open. Of course the turning of the key in the other direction when the door is closed raises the locking lever 129 into its full line locking position and then allows the releasing levers 131 to snap under it and hold the parts in locked position.

This invention has been described in connection with a number of illustrative embodiments, forms, arrangements, proportions, materials, connections and methods of operation, to the details of which disclosure the invention is not of course to be limited, since what is claimed as new and what is desired to be secured by Letters Patent is set forth in the appended claims.

1. In locking devices for elevator doors, an angularly arranged door catch provided

- with a slot and adapted to be mounted on an elevator door, a coöperating locking bolt having a roll locking member adapted to coöperate with said stop, a lock casing in which said locking bolt is mounted and which is adapted to be supported adjacent a door opening, a ratchet formed on said locking bolt, a stem and cushioning plunger connected to said locking bolt, a cushioning cylinder charged with oily cushioning fluid in which said plunger operates, a return spring tending to restore said locking bolt to receiving position, an alining device to adjust the receiving position of said bolt with respect to said catch, a toothed detent coöperating with said ratchet to hold said bolt in locking position, a detent spring normally forcing said detent against said ratchet, a detent extension projecting from said lock casing, a release device mounted on said door and comprising a release bolt to coöperate with said detent extension and a release lever to release said detent and to simultaneously open said door.
2. In locking devices for doors, an angularly arranged catch provided with a slot, a coöperating locking bolt having a roll locking member adapted to coöperate with said slot, a lock casing in which said locking bolt is mounted, a ratchet formed on said locking bolt, a stem and cushioning plunger connected to said locking bolt, a cushioning cylinder charged with oily cushioning fluid in which said plunger operates, a return spring tending to restore said locking bolt to receiving position, an alining device to adjust the receiving position of said bolt with respect to said catch, a toothed detent coöperating with said ratchet to hold said bolt in locking position, a detent spring normally forcing said detent against said ratchet, and a release device to release said detent and to simultaneously open said door.
3. In locking devices for doors, an angularly arranged catch provided with a slot, a coöperating locking bolt having a locking member adapted to coöperate with said slot, a lock casing in which said locking bolt is mounted, a stem and cushioning plunger connected to said locking bolt, a cushioning cylinder charged with cushioning fluid in which said plunger operates, a return spring tending to restore said locking bolt to receiving position, an alining device to adjust the receiving position of said bolt with respect to said catch, a detent to hold said bolt in locking position, a detent spring normally forcing said detent against said bolt, and a release device to release said detent and to simultaneously open said door.
4. In locking devices for doors, an angularly arranged catch provided with a slot, a coöperating locking bolt having a locking member adapted to coöperate with said slot, a cushioning device connected to said lock-

ing bolt, a return spring tending to restore said locking bolt to receiving position, and a detent to hold said bolt in locking position.

5. In locking devices for elevator doors, an angularly arranged door catch provided with a slot and adapted to be mounted on an elevator door, a coöperating locking bolt having a locking member adapted to coöperate with said slot and which is adapted to be supported adjacent a door opening, a ratchet formed on said locking bolt, a cushioning device connected to said locking bolt, a return spring tending to restore said locking bolt to receiving position, and a detent coöperating with said ratchet to hold said bolt in locking position and prevent opening movement of said door from an approximately closed position.

6. In locking devices for elevator doors, an angularly arranged door catch provided with a slot and adapted to be mounted on an elevator door, a coöperating locking bolt having a locking member adapted to coöperate with said slot and which is adapted to be supported adjacent a door opening, a cushioning return device connected to said locking bolt tending to restore the same to receiving position, a detent to hold said locking bolt in locking position, a releasing contact arm revolubly mounted on said detent, a releasing cam on said detent coöperating with said arm to disengage said detent when said releasing arm is actuated and a releasing device adapted to be mounted on the elevator and actuate said releasing arm when the elevator comes into coöperation with the door opening.

7. In locking devices for elevator doors, a door catch adapted to be mounted on an elevator door, a coöperating locking member, a detent to hold said locking member in locking position, a releasing contact arm revolubly mounted on said detent, a releasing cam on said detent coöperating with said arm to disengage said detent when said releasing arm is actuated and a releasing device adapted to be mounted on the elevator and actuate said releasing arm when the elevator comes into coöperation with the door opening.

8. In locking devices for doors, a catch provided with an angularly arranged slot, a coöperating locking bolt having a locking member adapted to coöperate with said slot, a fluid cushioning device connected to said locking bolt, means connected with said cushioning device to regulate its cushioning action on the closing of said locking device, and a detent to hold said bolt in locking position.

9. In locking devices for doors, an angularly arranged catch, a locking member adapted to coöperate with said catch and be moved transversely during the closing move.

ment of the locking device and a detent co-operating with said locking member to hold the same locked in a number of positions and prevent opening movement after said locking device has moved into approximately closed position.

10. In locking devices for elevator doors, a slotted angularly arranged catch adapted to be mounted at an angle to the line of travel of the elevator door, a coöperating locking member adapted to coöperate with said catch and to enter and be moved transversely by said slot during the closing movement of the door, a cushioning return device connected to said locking member tending to restore the same to receiving position

and a detent to hold said locking member locked in a number of positions.

11. In locking devices for doors, a slotted angularly arranged catch adapted to be mounted at an angle to the line of travel of the door, a coöperating locking member adapted to coöperate with said catch and to enter and be moved transversely by said slot during the closing movement of the door and a detent to hold said locking member locked in a number of positions.
